UNITED STATES PATENT OFFICE.

CHARLES T. REDFIELD, OF GLEN HAVEN, NEW YORK.

DESIGN FOR AN ANTIRATTLING PLATE.

SPECIFICATION forming part of Design No. 28,983, dated July 5, 1898.

Application filed June 6, 1898. Serial No. 682,774. Term of patent 7 years.

To all whom it may concern:

Be it known that I, CHARLES T. REDFIELD, residing at Glen Haven, in the county of Cayuga and State of New York, have invented and produced a new and original Design for Antirattling Plates, of which the following is a specification, reference being had to the accompanying drawings, forming part thereof, in which—

10 Figure 1 is a perspective view, Fig. 2 is an edge view, and Fig. 3 is a top plan view, of an antirattling plate embodying my design.

The leading feature of my design for antirattling plates consists in the article forming 15 the subject-matter of the illustration. The tongue-like wing A is deflected from the plane of the main or base portion B of the plate. At

one end of the portion B, I provide the upright flange C, having the notch D in its upper edge, while at the other end of the portion B, I provide the upright slightly-inclined wing E, whose upper edge is bifurcated and has the lateral projections F. The opposite edges of the portion B are curved nearly from end to end on lines simulating the line of beauty. ²⁰ ²⁵

Having described my invention, what I claim as new, and desire to secure by Letters Patent, is—

The design for an antirattling plate, as herein shown and described.

CHARLES T. REDFIELD.
